CURTAIN STRETCHER

Abel E. Garner, New York, N. Y., and Paul W. Getschman, Kenosha, Wis., assignors to World'sbest Industries, Inc., Cudahy, Wis., a corporation of Wisconsin

Application May 29, 1950, Serial No. 164,928

3 Claims. (Cl. 45—24)

1

The invention relates to fabric stretchers. The usual form of curtain or other fabric stretcher is adapted to take only one size or dimension of fabric or curtain for each set up of the stretcher. If fabric or curtains of different sizes are to be dried in a stretched condition, then either the fabric or curtains have to be treated one at a time or more than one stretcher has to be used. In the first instance there is a loss of time, and in the second instance the expense of the equipment is doubled. The main object of the present invention is to provide a fabric stretcher which by the addition of a second adjusting bar and a second bottom bar enables stretching of fabrics of different widths and lengths at the same time.

A further object of the invention is to provide a fabric stretcher employing two adjusting bars and two bottom bars in which the second adjusting bar is provided with an easel mounting which cooperates with a similar mounting on the end bar to support the stretcher in upright position, thereby simplifying the structure over that of our copending application Serial No. 109,676, now abandoned, filed August 11, 1949, for Curtain Stretcher. This application is a continuation in part of the above mentioned application as to claims for all common subject matter.

The invention further consists in the several features hereinafter set forth and more particularly defined by claims at the conclusion hereof.

In the drawings:

Fig. 1 is a front elevation view of a curtain stretcher embodying the invention, parts being broken away;

Fig. 2 is an end elevation view;

Fig. 3 is a detailed horizontal sectional view taken on the broken line 3—3 of Fig. 1;

Fig. 4 is a detailed vertical sectional view taken on the line 4—4 of Fig. 1.

The curtain frame embodying the invention comprises a top bar 5, spaced bottom bars 6 and 7, an end bar 8, a vertical center bar 9, and spaced horizontally or laterally adjustably mounted adjusting bars 10 and 11 secured together by various fittings to form a stretching frame, the top and bottom bars, the end bar and both of the adjusting bars having pins 12 on which portions of the damp curtains are impaled to stretch the fabric and hold it in this condition until dried.

It will be noted from Fig. 1 that by providing an additional bottom bar, and an additional adjusting bar that we have provided two stretching frames in one apparatus, for with this arrangement small size curtains may be stretched on the

2

frame composed of bars 5, 8, 10 and 6 and large size curtains may be stretched on the frame composed of bars 5, 8, 11 and 7, at the same time.

With the usual types of frames, the adjusting bar has a flush joint connection with the top bar, as shown for example in U. S. Letters Patent No. 2,448,574, of September 7, 1948, to Werner H. Bothe, and a similar flush joint connection is made between the end bar and the bottom bar, so that the pinning of the jointed bars is in substantially the same plane. In the present invention the same form of clamp 13 is used as that shown and described in said patent, and the pinning of adjusting bar 11 is in substantially the same plane as that of the top bar, and the pinning of the bottom bar 7 is similarly co-planar with that of the bar 8, and to permit of such types of connection the anchoring member 14 of the Bothe clamp, as shown in Fig. 4, has an offset 15 20 therein so as to offset the adjusting bar 10 rearwardly relative to the top bar 5 against which it abuts, and a similar offset 16 is provided in the anchoring member 17 for the Bothe clamp to offset the bottom bar 6 rearwardly relative to the 25 end bar 8 against which it abuts, as shown in Fig. 3. By this arrangement the pins 12 on the bars 10 and 6 are offset back of the pins 12 on the bars 11 and 7, so that the pins of the smaller size frame heretofore mentioned will not interfere with those of the larger size frame in the attachment of the curtains thereto. It is also to be noted that the adjusting bar 10 extends down 30 behind the bottom bars 6 and 7 and is clamped in abutting engagement with the back of the bottom bar 6 by a clamp device 18 of known form 35 having a part 19 engaging the bottom bar 7. The adjusting bar 11 extends down in front of the bottom bars 6 and 7 and is clamped in abutting engagement with these bars by clamp devices 40 similar to the clamp device 18 and including a channel member 20 engageable with the bottom bar, an angled bar 21 engageable with either the bar 6 or 7 and the bar 11, a threaded bolt 22 anchored to the member 20 and extending 45 through a hole in bar 21, and a wing nut 23 threaded onto the bolt 22 and engaging the bar 21. The center bar 9 is adjustably clamped to the bottom bars and the top bar by suitable clamps.

It will be noted that the adjusting bar 11 is of the same length as the end bar 8, and each of these bars is provided with a leg 24 pivotally connected at its back to said bar by a bracket 25 carrying a hinge pin 26 extending through the upper portion of the leg or pivotally connected to

a portion of said bar in any other suitable manner. The leg 24 is braced relative to its supporting bar by a brace link 27 pivotally connected by a pin 28 to said leg and having a hooked end 29 engageable with a pin 30 mounted in the outer edge of either the bar 11 or the bar 8. The leg is shown here in connection with the bar 11, but the same type of leg and mounting is used with the end bar 8. Thus the end bar 8 and adjusting bar 11 with their easel type legs 24 act to support the entire stretcher frame in an upright though slightly inclined position, as shown in Fig. 2, and by forming the vertical bar 11 as a leg member the usual additional end bar and some of its fittings and their cost are eliminated. Instead of an easel leg 24, the bars 8 and 11 may form part of the supporting means for the stretcher by mounting the bottom ends of these bars in foot members, or the bars 8 and 11 themselves may form the legs when the stretcher is leaned against a wall.

The above constructions at only the additional cost of the two bars 7 and 11 provides a frame on which two curtains of different widths and lengths may be stretched and dried at the same time. Also considerable time and labor in setting up the frame as compared to two separate stretchers is saved.

We desire it to be understood that this invention is not to be limited to any particular form or arrangement of parts except in so far as such limitations are included in the claims.

What we claim as our invention is:

1. In a fabric stretcher, the combination of a top bar provided with pinning, an end bar provided with pinning, vertically disposed spaced adjusting bars provided with pinning, horizontally disposed spaced bottom bars, substantially equal in length to the top bar, provided with pinning, means for securing said bars together as a unitary frame to form a larger fabric receiving frame and a smaller fabric receiving frame of which said top bar and end bar form common elements, the pinning of the adjusting bar for the larger frame being in substantially the same plane as that of the top bar and the pinning of the adjusting bar for the smaller frame being rearwardly offset relative to that in the top bar, the pinning of the bottom bar for the smaller frame being rearwardly offset relative to that of said end bar, the securing means for the bars including clamping devices securing both of the bottom bars to the adjusting bar for the larger frame, the end bar and the adjusting bar for the larger frame each provided with a pivoted leg operatively braced relative thereto whereby said end bar and larger frame adjusting bar form supporting uprights for the stretcher.

2. In a fabric stretcher, the combination of a top bar provided with pinning, an end bar provided with pinning, vertically disposed spaced adjusting bars provided with pinning, horizontally disposed spaced bottom bars, substantially equal in length to the top bar, provided with pinning, means for securing said bars together as a unitary frame to form a larger fabric receiving frame and a smaller fabric receiving frame of which said top bar and end bar form common elements, the pinning of the adjusting bar for the larger frame being in substantially the same plane as that of the top bar and the pinning of the adjusting bar for the smaller frame being rearwardly offset relative to that in the top bar, the pinning of the bottom bar for the smaller frame being rearwardly offset relative to that of said end bar, the securing means for the bars including clamping devices securing both of the bottom bars to the adjusting bar for the larger frame, the end bar and the adjusting bar for the larger frame forming part of the supporting means for the stretcher.

3. In a fabric stretcher, the combination of a top bar provided with pinning, an end bar provided with pinning, vertically disposed spaced adjusting bars provided with pinning, horizontally disposed spaced bottom bars provided with pinning, means for securing said bars together as a unitary frame to form a larger fabric receiving frame and a smaller fabric receiving frame of which said top bar and end bar form common elements, the pinning of the adjusting bar for the larger frame being in substantially the same plane as that of the top bar and the pinning of the adjusting bar for the smaller frame being rearwardly offset relative to that of the top bar, the pinning for the bottom bar for the larger frame being in substantially the same plane as that of the end bar, and the pinning of the bottom bar for the smaller frame being rearwardly offset relative to that of said end bar, said horizontally disposed spaced bottom bars both extending the length of the larger frame.
